SCREW DRIVER ALIGNING TOOL

Filed April 2, 1945

UNITED STATES PATENT OFFICE

2,565,505

SCREW DRIVER ALIGNING TOOL

William J. Lamb, South Euclid, Ohio, assignor, by
mesne assignments, to Armstrong Cork Com-
pany, Lancaster, Pa., a corporation of Pennsyl-
vania

Application April 2, 1945, Serial No. 586,206

5 Claims. (Cl. 144—32)

1

This invention relates to tools, and particularly to screw drivers and holding and guiding attachments therefor.

The primary object of this invention is to provide a tool which facilitates the insertion of a screw into a preperforated material, and which tool is rapid and convenient to use and which may be more easily fed or loaded.

Another object of the invention is to construct such tool so that the material proximate the hole where the screw is to be inserted is visible at all times and so that the surface of the material is practically untouched and remains unmarred and undamaged.

A further object is to provide a tool of the type mentioned that retains the screw when the tool is in its normal position.

Still another object is to provide such tool with an adjustable head which permits its use with material having different perforation spacings.

A still further object is to provide a screw driver attachment of the type stated that is adjustable so that screws of different lengths may be easily accommodated and which adjustments permit screws to be driven uniformly to a predetermined depth into the material.

These and other objects of the invention will become apparent from a reading of the following description and claims, together with the accompanying drawing, in which like parts are referred to and indicated by like reference characters and wherein:

Figure 1 is a view of the invention showing it attached to a portable motor and engaged with material to be secured or mounted;

Figure 2 is a vertical cross-sectional view of the screw driver and accessory, and particularly showing the former in its normal position and having a screw retained therein;

Figure 3 is a vertical cross-sectional view of the screw driver and accessory and particularly showing the screw driver in its extended position;

Figure 4 is a view similar to that of Figure 3 but showing the device adjusted to accommodate a longer screw;

Figure 5 is an elevational view of a portion of the screw driver and accessory, and particularly showing an alternate method of mounting the spring used therewith;

Figure 6 is a top or front end view of the device;

Figure 7 is a horizontal cross-sectional view of the device and a piece of material used therewith, taken substantially along the line and in

2

the direction of the arrows 7—7 of the Figure 3; Figure 8 is an exploded view of the device showing certain portions thereof partly in section; and

Figure 9 is a vertical cross-sectional view of the top portion of the device, and particularly showing parts thereof adjusted to prevent contact with the surface of the material being mounted.

10 Conducive to a clearer understanding of this invention, it should be pointed out that this tool is designed to facilitate the mounting of perforated acoustic tile to ceilings or other suitable bases or surfaces 7. The tiles for which this is intended have regularly spaced and aligned perforations or recesses such as are indicated by the reference character 9 in the Figures 1 and 7. Most of the tiles have a finished flat surface which it is desired to preserve in its original clean and unmarred state. However, different brands or makes of tiles manufactured by different companies vary in that the perforations 9 or recesses have different spacings.

15 Also, some tiles 8 are perforated almost entirely through or are perforated to such an extent that the efficiency of screws 6 in such perforations is practically lost. It then becomes necessary to drive the retaining screws through an unperforated part of the tile, as in the manner indicated by the reference character 6a of the Figure 4. In this event, the screw is longer and the head thereof is not recessed in the tile 8.

20 Since acoustic tiles are not standard as to thickness, structure and design, and since the prior art tools of this type were not universal in their use or application, there is here provided two major and important means for adjusting the tool. These two adjusting means make the tool adaptable for use with practically all makes of acoustic tile and enable it to be used under conditions and for purposes not heretofore provided for.

25 The first major adjustment provides a quick and easy method of setting the screw driving member 28 so that the blade 28 thereof will reach a predetermined position when fully projected. The second major adjustment provides a quick and easy method of positioning the guide pins 36 to accommodate different makes of tile, as set forth in the heretofore mentioned objects. A third adjustment, not found in prior art tools, enables the guide pins 36 to be extended or retracted as desired so that the outer visible surface of the tile is not touched by the tool head.

This eliminates all possibility of accidental scratching or marring of the tile surfaces.

Referring to the drawing, there is shown in the Figure 1, a tool made in accordance with this invention mounted on a portable electric motor 5. The tool itself consists primarily of three members; namely, the body member, the screw driving member and the adjustable cap member. Each of these members are broadly indicated by the reference characters 10, 20 and 40 and each will be described in detail and in the order stated.

The body member 10 consists of a tubular shell which has a longitudinal channel 11 extending therethrough. The outer surface of the body is knurled as is indicated by the character 17 to make the device more convenient to handle. The lower end of the shell body has an external thread 18 therein, as is clearly shown in the drawing. Its upper end has a shoulder portion 13 which is of a diameter slightly larger than 13 which is of a diameter slightly larger than the diameter of the shell body. Above the shoulder portion 13 there is a tapered or somewhat conical head portion 12. The portion of the longitudinal channel passing through the head and shoulder portions 12 and 13 is constricted and forms thereat a narrowed channel or passage 15 in which the screw 6 is placed and in which the screw driver blade 28 moves. The portion of the shoulder inside the body adjacent to the passage 15 forms a seat 14 which engages the top end of the compression spring 31.

The tapered or conical head portion 12 is concentric with the tubular body and its narrow top edge is relatively thin and is the very small portion that might actually contact the surface of the tile.

The shoulder portion 13 is also concentric with the tubular body and its top flat surface is provided with various sets of holes 16. One set of holes, as for example the set indicated by the reference characters 16a in the Figure 6, are close together; another set, as for example those indicated by the reference characters 16b and 16d, are spaced farther apart. The holes of each set are equidistant from the head 12 and are diametrically in line therewith. In the Figure 6, the horizontally aligned holes 16c have the hereinafter described pair of guide pins 36 mounted therein.

The screw driving member 20 consists of a round drive shaft 22, the bottom end of which is provided or formed with a detent or recess 26 for suitable engagement with the collet or chuck on the portable motor 5. The upper end of the shaft 22 has a recessed collar 23 affixed thereto. This recess of the collar 22 receives the shank 21 of the removable and replaceable screw driver. The bottom of the shank 21 is held in place in the recessed collar by the small set screw 24. The compression spring 31 fits loosely around the shank 21 of the screw driver and its lower coil rests on the collar 23 and its upper coil engages the seat 14 on the inside portion of the shoulder 13.

A second collar 25 is mounted on the drive shaft 22 below the hereinafter described cap member 40. The position of this collar 25 is variable and may be set by a simple set screw as shown, and provides an upward movement stop for the member 20.

A small piece of metal tubing 27 is mounted loosely around the shaft 22, just below the collar 23. The lower end of this tube rests on the inside of the flange 42 and its upper end is

engageable with the bottom of the collar 23. This tube 27 provides a simple but effective downward movement stop for the screw driving member 20. The spring 31 tends to urge the cap 23 and the tube 27 together as shown in the Figure 2, and which position is the normal or non-operating position of the respective members.

The guide pin members 36 are simply short pieces of thin bar metal. The lower ends thereof have external screw threads 37 thereon which engage any of the heretofore mentioned sets of holes 16 in the shoulder 13. The outside diameters of the pins 36 are slightly smaller than the inside diameters of the perforations 9 in the tile, and the top ends thereof are substantially flat as shown. The pins 36 have relatively long threaded portions 37 and may be inserted in the holes 16 to depths determinable by the type of tile being used and by the particular manner of mounting the same.

The cap member 40 consists of a short piece of tubing having an internal screw thread 41. The screw thread 41 engages the outside screw thread 18 of the body member 10. The bottom end of the member 40 has the inside flange 42 upon which rests the tube 27 and against which the stop collar 25 abuts when the screw driving member reaches its farthest position. It also has an axial or longitudinal opening 43 through and in which the shaft 22 passes and rotates.

The internally threaded ring 44 engages the screw threads 18 of the body member 10 and also tightly abuts and engages the open end of the cap member to lock it in a fixed or predetermined position in the manner of a lock nut. Both parts of the cap member 40 may have knurled outer surfaces if desired, to make the adjustments more convenient.

For operation, the pair of pins 36 are inserted in a set of holes 16 which match the spacing of the perforations 9 of the tile to be secured or mounted. The two pins 36 are then screwed in or out of their respective holes 16 to either allow the top narrow brim of the head portion 12 to be in close contact with the tile, as shown in the Figures 1, 2, 3 and 4, or to be spaced therefrom as shown in the Figure 9.

The cap member 40 is then raised or lowered on the body member 20 to fix the maximum upward or forward position to which the blade 28 of the screw driver may extend. This position may be one as shown in the Figure 3 for recessing the screw head, or it may be as shown in the Figure 4 where the screw head is allowed to remain exposed on the surface of the tile.

Finally the stop collar 25 is positioned and fixed on the shaft 22 depending on the length of the screw 6 that is to be inserted. Lowering the collar 25 on the shaft 22 permits a longer or deeper drive, while raising it and bringing it closer to the recessed collar 23 shortens the drive and permits less longitudinal movement of the screw driving member 20.

Among the many advantages that this device has over prior art devices designed for the kind of work stated, is that the normal position of the screw driver blade 28 is well below the brim of the head portion 12. Therefore there is always a receptacle for receiving the screws 6. The screw 6 will not drop out of the tool unless it is pointed downward. Either hand may be used for feeding screws into the receptacle and both hands of the operator may be used to hold and

support the motor 5. The device is therefore less tiresome to use than are similar tools heretofore known or patented.

Furthermore, it should be pointed out that with this tool practically all of the material around where the screw 6 is being inserted is visible. This feature is important because it enables the operator to detect imperfect insertion or operation before damage may result to the tile. If, for example, the screw 6 should happen to be imperfect or if it should meet some unseen obstacle in the base 7, it is apt to go askew and continued driving therefore is very likely to tear or mutilate the acoustic tile which itself is only a soft, felted, frangible product.

Having thus disclosed the invention in its preferred form, it should be understood that the description and illustrations thereof are suggestive only. It should also be understood that since there may be other forms or modifications of the invention, no limitations thereof are intended, except those specifically imposed thereon by the breadth and scope of the appended claims.

I claim:

1. A tool of the type described, comprising in combination, a tubular body member having a shoulder portion thereon, the said shoulder portion having sets of diametrically arranged holes therein, each set of holes being differently spaced, a pair of pins mountable on the shoulder portion and engageable with any of the said sets of holes, and a screw driving member slideably mounted in the body member and operable between the said pins.

2. A tool of the type described, comprising in combination, a tubular body member having head and shoulder portions integral therewith, the said head portion being tapered for minimum contact with the material to be secured, the said shoulder portion being in spaced relation with the said material and having sets of diametrically arranged holes therein, each set of holes being differently spaced, a pair of pins threadedly engageable with any of the said sets of holes and being capable of engaging perforations in the said material, and a screw driving member including a screw driver and a drive shaft therefor slideably mounted in the body member, the said screw driver being movable longitudinally through the head portion and rotatable between the pair of pins.

3. A tool of the type described, comprising in combination, a tubular body member having head and shoulder portions integral therewith, the said head portion being tapered for minimum contact with the material to be secured, the said shoulder portion being in spaced relation with the said material and having sets of diametrically arranged holes therein, each set of holes being differently spaced, a pair of pins 60 threadedly engageable with any of the said sets of holes and being capable of engaging perforations in the said material, a screw driving member including a screw driver and a drive shaft therefor slideably mounted in the body member, the said screw driver being movable longitudinally through the head portion and rotatable between the pair of pins, and a spring means 65 between and engaging the said members tending to force the screw driving member inwardly of the head portion.

4. A tool of the type described, comprising in combination, a tubular body member having head and shoulder portions integral therewith, the said head portion being tapered for minimum contact with the material to be secured, the said shoulder portion being in spaced relation with the said material and having sets of diametrically arranged holes therein, each set of holes being differently spaced, a pair of pins threadedly engageable with any of the said sets of holes and being capable of engaging perforations in the said material, a screw driving member including a screw driver and a drive shaft therefor slideably mounted in the body member, 10 the said screw driver being movable longitudinally through the head portion and rotatable between the pair of pins, the said drive shaft having a collar thereon, and an adjustable cap member mounted on the body member encircling the said drive shaft and engageable with the collar thereon and being capable of fixing the normal position of the screw driving member.

5. A tool of the type described, comprising in combination, a tubular body member having head and shoulder portions integral therewith, the said head portion being tapered for minimum contact with the material to be secured, the said shoulder portion being in spaced relation with the said material and having sets of diametrically arranged holes therein, each set of holes being differently spaced, a pair of pins 20 threadedly engageable with any of the said sets of holes and being capable of engaging perforations in the said material, a screw driving member including a screw driver and a drive shaft therefor slideably mounted in the body member, the said screw driver being movable longitudinally through the head portion and rotatable between the pair of pins, the said drive shaft having a collar thereon, and an adjustable cap member mounted on the body member encircling the said drive shaft and engageable with the collar thereon and being capable of fixing the normal position of the screw driving member.
